PADLOCK

William E. Evans, Waterbury, Conn., assignor to
The Waterbury Lock & Specialty Company,
Milford, Conn., a corporation of Connecticut

Application December 28, 1938, Serial No. 248,075

4 Claims. (Cl. 70—38)

My invention relates to an improvement in padlocks and particularly to that type of padlocks which are provided with longitudinally-movable shackles having one leg shorter than the other, so that when the shackle is moved outward it may be turned to free the shorter end from the padlock-casing.

The object of the invention is to simplify the construction and arrangement of parts, so as to reduce the cost of producing and assembling of the parts, so that, if desired, padlocks of very small size may be produced without sacrificing the element of safety.

With the above and other objects in view, as will appear to those skilled in the art from the present disclosure, this invention includes all features in the said disclosure which are novel over the prior art.

In the drawings:

Fig. 1 is a front view of a padlock embodying my invention;

Fig. 2 is a side view of the same;

Fig. 3 is a front view on a larger scale with the front plate removed;

Fig. 4 is a rear view with the rear plate removed;

Fig. 5 is a sectional view on the line 5—5 of Fig. 3, the front and rear plates being shown in assembled position;

Fig. 6 is a sectional view on the line 6—6 of Fig. 3, the front and rear plates being shown in assembled position;

Fig. 7 is a front view of the casing with all parts removed;

Fig. 8 is a rear view of the same;

Fig. 9 is a perspective view of the housing-member detached;

Fig. 10 is a perspective view of the keyhole-button detached; and

Fig. 11 is a perspective view of a tumbler or key-change plate detached.

In carrying out my invention, I employ a casing 15 which may be readily cast in metal, synthetic resin, such as Bakelite or other suitable material, with a central rectangular opening 16 and with a deep vertical round shackle recess 17 at one side and with a shallow round shackle recess 18 at the opposite side. One of the sides 19 of the opening 16 is formed with transverse grooves 20, 21, 22 and the other side 23 is formed with corresponding grooves 24, 25, 26. The sides 19 and 23 of the opening 16 are also provided with notches 27—28, the notch 28 intersecting the shackle-recess 17.

At the bottom of the casing is a hole 29. The

front of the casing is formed with an undercut wall 30 which is interrupted by a stop-lug 31, and the rear of the casing is formed with a similar wall 32 and lug 33.

Seated in the hole 29 is a keyhole-button 34 which is of cup-shape with an outwardly-extending annular flange 35 to prevent the button from passing through the hole 29, and the button is also formed in its bottom with a keyway-slot 36. A keyway change-plate or tumbler 37 is seated in the grooves 20, 24, and a similar tumbler may be seated in the grooves 21, 25. These tumblers are preferably formed from sheet-metal, with an offset central portion 38 and with shoulders 39 which seat upon the sides of the opening 16. If only one tumbler is employed, it may be entered into either the grooves 20, 24 or the grooves 21, 25, and may be arranged with the offsets 38 extending either upwardly or downwardly, thus providing for a variety of key changes.

The shackle 40 is of U-shape with a long leg 41 and a short leg 42. The end of the long leg 41 is formed with a spring-chamber 43 to receive a helical spring 44 which has a bearing on the bottom of the shackle-recess 17. The leg 41 is formed with an annular groove 45. A flat metal spring 46 is bent to form a head 47, a long leg 48 and a short leg 49, and this end terminates in a finger 50. The head is seated in the notch 27, the long leg 48 extending into the notch 28 to enter the groove 45 in the shackle-leg 41. A sheet-metal housing 51 is formed with an upper arm 52 and a lower arm 53. The upper arm is formed with a perforation 54 to form a seat for the inner end of a key, and below the arm 52 is a slot 55 to receive the spring-finger 50. The lower arm 53 is formed with a key-slot 56. The upper arm 52 is passed through the grooves 22 and 26, and the lower arm 53 stands over the key-hole-button 34, and the corners 57, 58 of the upper arm 52 are turned down onto the casing so as to lock the housing in position. One edge of the upper arm 52 extends into the shackle-recess 17 and into the groove 45 of the shackle-leg 41, so as to limit the outward movement of the shackle, the housing 51 also holding the other parts of the lock in proper position.

When the proper key is inserted and turned, the long leg of the spring will be moved out of the groove in the long leg of the shackle so as to release the same, and allow it to be raised by its spring and lift the short leg out of engagement with the casing, the outward movement of the shackle being limited by the edge of the housing.

A concave-convex face-plate 59 is placed within the wall 30, a notch 60 engaging the stop-lug 31, and a similar back-plate 61, having a notch 62, is placed within the wall 32 to engage with the stop-lug 33, and these plates are pressed so as to radially expand and engage with the walls. By providing the notches and stop-lugs, the proper position of the plates is assured, if the outer face-plates are stamped with numbers or 10 ornamentation.

It will be seen from the foregoing that I may produce attractive padlocks in very small sizes, as well as larger ones, which are very simple in construction of parts and method of assembly.

15 The invention may be carried out in other specific ways than that herein set forth without departing from the spirit and essential characteristics of the invention, and the present embodiment is, therefore, to be considered in all respects 20 as illustrative and not restrictive, and all changes coming within the meaning and equivalency range of the appended claims are intended to be embraced therein.

I claim:

25 1. A padlock comprising a casing having a central opening, transverse grooves and spring notches in the side walls of the casing, a key tumbler mounted in said grooves, a vertically-movable shackle, a spring to hold the shackle 30 in a locked position, said spring formed with head seated in one notch, one leg of the spring extending into the other notch to engage the shackle, the other leg formed with a finger, and a housing mounted in the casing and adapted 35 to hold all of the parts of the lock in position and formed with a slot to receive said finger.

2. A padlock comprising a casing having a rectangular central opening, transverse housing and tumbler grooves in the side walls of the opening, a key tumbler mounted in said tumbler grooves, a vertically-movable shackle, a spring to hold the shackle in a locked position, and a housing having a lower arm formed with a key slot and an upper arm seated in the housing grooves and interlocked therewith to hold the tumbler and spring of the lock in position. 10

3. A padlock comprising a casing having a rectangular central opening, transverse housing and tumbler grooves in the side walls of the opening, a key tumbler having an offset central portion mounted in said tumbler grooves, a vertically-movable shackle, a spring to hold the shackle in a locked position, and a housing having a lower arm formed with a key slot and an upper arm seated in the housing grooves and interlocked therewith to hold the tumbler and 15 spring of the lock in position. 20

4. A padlock comprising a casing having a rectangular central opening, transverse housing and tumbler grooves in the side walls of the opening, a keyhole at the lower end of the central opening, a keyhole-button in said keyhole, a key tumbler mounted in said tumbler grooves, a vertically-movable shackle, a spring to hold the shackle in a locked position, and a housing having a lower arm formed with a key slot and an upper 25 30 arm seated in the housing grooves and interlocked therewith to hold the shackle against removal and the tumbler, spring and keyhole-button of the lock in position.
